UNITED STATES PATENT OFFICE.

HARRY A. WINTERMUTE, OF NEW YORK, N. Y., ASSIGNOR TO RESEARCH CORPORATION, OF NEW YORK, N. Y., A CORPORATION OF NEW YORK.

METHOD OF AND APPARATUS FOR SEPARATING LIGHT MATERIALS FROM GASES.

Application filed February 11, 1925. Serial No. 8,491.

To all whom it may concern:

Be it known that I, HARRY A. WINTERMUTE, a citizen of the United States, residing at New York, in the county of New York and State of New York, have invented certain new and useful Improvements in Methods of and Apparatus for Separating Light Materials from Gases, of which the following is a specification.

10 This invention relates to the separation of suspended material from gases and more in particular to electric separation of light fluffy material such as carbon black.

15 For a full understanding of the invention reference is made to the accompanying drawing which is a more or less diagrammatic representation of what I consider a preferred embodiment of the invention.

20 In the drawing 10 represents a tubular collecting electrode and 11 a wire discharge electrode commonly used in the art of electric precipitation. It is understood that this form of precipitator is merely representative of electric precipitators in general and 25 has no particular or special significance. Any other precipitator in which the collecting electrode surfaces define gas passages may find application.

20 The lower end of the electrodes 10 and 11 terminates in a lower header 12 and adjacent the header 12 is a compartment 13 for housing the insulator 14 on which is supported a rod 15 or the like for keeping the discharge electrode 11 centered, the usual ball 16 holding the wire electrode 11 taut.

The gas stream carrying the material in suspension enters through the inlet 17.

Above the header 12 is disposed a settling chamber 18 which is in communication with the interior of the collecting electrode 10 through a perforated portion 19 thereof. The collecting electrode 10 terminates above the settling chamber.

45 The gas stream entering through inlet 17 passes up through the tubular collecting electrode 10 and the suspended particles under the action of the discharge electrode are precipitated against the collecting surface.

I have found that when the velocity of the

gas stream is properly adjusted the deposit 50 is dislodged from the electrode surface in the form of large agglomerated masses and carried along the walls of the collecting electrode and may then be separated from the 55 gas stream.

I have also discovered that these agglomerated masses moving with the gas jump back and forth between the discharge electrode and the collecting electrode much the same as a pith ball jumps back and forth between two oppositely charged plates. When they reach an open space in the collecting electrode, they jump back and forth until the momentum carries them out of the field of influence. They then drop due to 65 gravity action and may be collected.

I have also found it unnecessary to use any of the other methods commonly employed in electrical precipitation, such as rapping, scraping or brushing, for dislodging the material precipitated on the electrodes. This self-cleaning feature is very desirable and advantageous in all precipitation work and especially so in the precipitation of lamp black.

75 This discovery I may practically utilize in several ways. In actual practice I have used a $\frac{1}{8}$ " rod wound spirally with the convolutions about 1" apart to form the perforated section 19. Other constructions may 80 be found suitable for the purpose. While a plain opening is satisfactory to a certain extent, I have found that provisions for maintaining an electric field through the opening are much more effective and are a practical 85 desideratum. The electric field may be produced by any metallic frame or screenwork connected with the collecting electrode and providing openings large enough for the agglomerated masses to freely pass through.

90 Although there is considerable latitude in regard to the velocity of the gas stream in its relation to the potential difference and gap between the electrodes and the length of the electrodes and the condition of the gases, 95 I have found in practical tests with tubular collecting electrodes of about 12" diameter and 18 feet long, that a gas velocity of 7-9

ft. sec. gives very good results. The dislodgement of agglomerated particles and their motion became apparent about four minutes after starting operations and continued uninterruptedly so long as the gas flow was maintained.

When the agglomerated particles reach the perforated section, the to and fro motion under the action of the electric field eventually carries them into the perforations beyond a critical point where the action of the field cannot pull them back and they drop there while the gas itself passes out of the terminal end of the passage defined by the tube or other collecting electrodes.

In the settling chamber the particles are out of the sphere of the kinetic action of the gas stream and can settle and may then be removed.

The principle of operation is not related to what is sometimes called "electric wind". In fact, I found that the operation may be carried out with relatively low voltages and that the discharge electrode may advantageously be charged positively rather than negatively as is the general practice for obtaining the highest potential gradient.

The operation depends essentially upon the application of an electric field sufficient to precipitate the fine particles upon the collecting electrode, and upon the rate of gas flow. These forces must be so controlled that the agglomerated material is dislodged and caused to move with a to and fro motion between the collecting and discharge electrodes and in a resultant direction substantially parallel with the gas flow to an opening through which it is removed.

As soon as the opening is reached, the support afforded by the collecting electrode surface up to the opening is no longer present so that the resultant movement of the agglomerated masses due to the kinetic action of the gas stream and the electric action is disturbed and the said masses drop out of the gas stream in the only direction in which they can drop, i. e. through the opening into the space where there is neither electric action nor a kinetic action of gas.

While the movement of the detached agglomerated masses out of the gas stream may be promoted by a slight negative pressure in the settling chamber relative to that in the passage way defined, I have found that such negative pressure is not necessary for successful operation.

While the mode of operation applies especially to the separation of carbon black or the like, it necessarily applies to all light fluffy materials having the physical characteristics of electrically precipitated carbon black.

I claim:

1. The method of separating light sus-

pended material from gases, which consists in passing a gas stream carrying the material in suspension through a passage, and subjecting the gas stream to an electric field causing a deposit of the material on the walls of the passage, the gas being passed through the passage at such velocity that under the action of the gas stream masses of the deposit are detached in agglomerated form and carried onwardly by the stream.

2. Method according to claim 1 including the step of collecting the agglomerated masses after detachment from the walls of the passage.

3. The method of separating light suspended material from gases, which consists in passing a gas stream carrying the material in suspension through an electric precipitator defining a passageway for said gas stream, under such conditions of velocity as to cause the particles deposited and agglomerated under the electric action to be dislodged from the collecting surface and to move parallel to the gas stream and then allowing the dislodged particles to move out of the gas stream under the action of an electric field.

4. The method of separating light suspended material from gases, which consists in passing a gas stream carrying the material in suspension through an electric precipitator defining a passageway, subjecting the gas stream to such electric action as to cause collection and agglomeration of the suspended material on the walls of the passage, controlling the rate of flow of the gas stream so as to cause the gases to dislodge the collected and agglomerated material and carry the same substantially parallel to the gas stream, and allowing the dislodged material to move out of the gas stream under the action of the electric field.

5. The method of separating light suspended material from gases, which consists in passing a gas stream carrying the material in suspension through an electric precipitator defining a passageway, subjecting the gas stream to such electric action as to cause collection and agglomeration of the suspended material on the walls of the passage, controlling the rate of flow of the gas stream so as to cause the gases to dislodge the collected and agglomerated material, and maintain continuously substantially clean electrodes.

6. Apparatus for separating light suspended material from gas, comprising a vertical tubular collecting electrode having an uninterrupted collecting surface from the bottom to near the top and a perforated portion near the top, defining relatively large openings and a discharge electrode extending through the collecting electrode.

7. Apparatus for separating light sus-

pended material from gas, comprising a vertical gas passage imperforate from the bottom to near the top and constituted at least in part by collecting electrode means, the 5 passage having near its top an opening and a screen in said opening, and a discharge electrode extending through the gas passage.

8. Apparatus according to claim 7, including a settling chamber surrounding the said gas passage and in communication there- 10 with through said screen.

In testimony whereof, I affix my signature.

HARRY A. WINTERMUTE.
